UNITED STATES PATENT OFFICE.

HORACE JAMES CHARLES, OF JACKSONVILLE, FLORIDA, ASSIGNOR, BY DIRECT AND MESNE ASSIGNMENTS, OF THREE-TENTHS TO THOMAS E. HAMPTON, OF JACKSONVILLE, FLORIDA, AND THREE-TENTHS TO DANIEL W. SHEA, OF TAMPA, FLORIDA.

SHIP-PROTECTOR.

1,185,983.

Specification of Letters Patent.

Patented June 6, 1916.

Application filed September 8, 1915, Serial No. 49,576. Renewed April 28, 1916. Serial No. 94,240.

To all whom it may concern:

Be it known that I, HORACE JAMES CHARLES, a citizen of the United States, residing at Jacksonville, in the county of Duval and State of Florida, have invented certain new and useful Improvements in Ship-Protectors; and I do hereby declare the following to be a full, clear, and exact description of the invention, such as will enable others skilled in the art to which it appertains to make and use the same.

My invention relates to improved means for protecting vessels from the attacks of automobile torpedoes, and it is intended to be applied either to men-of-war, or merchantmen, and more especially to merchantmen.

According to my invention I hinge, well below the water line, either to the bilge of the ship, or to the main or one of the bilge keels, a series of plates which may be normally drawn up against the side of the ship, but which, when the ship is in the danger zone, may be lowered into the water at such an angle that the torpedo striking the same will be deflected downward, and will dive under the keel of the ship, and pass free of the body of the vessel without entering the same. By having the angles of the plates when lowered sufficiently great, say 60°, the blunt nose of the torpedo will strike the plate without permitting the firing pin to strike at all; the result being that the nose of the torpedo is tilted downward and the torpedo passes beneath the ship without exploding. These metal plates need not necessarily be heavy at all, but need only be of sufficient thickness to withstand the ordinary usage and to stand the glancing blow of the automobile torpedo.

My invention will be understood by reference to the accompanying drawings, in which:—

Figure 1 shows diagrammatically a side elevation of a ship fitted with the improved torpedo protective device; Fig. 2 is a plan view of the same ship, showing the torpedo protective device in full lines in the raised position and in dotted lines in the lowered position; Fig. 3 is a perspective view showing part of the apparatus on a larger scale,

parts being shown in section and parts broken away; Fig. 4 shows a part of the protective screen detached, as seen from the side next the hull of the ship; and Fig. 5 is a plan view showing a modification, in which the plates are held outboard by rigid bars or beams.

A represents the body of the ship, and connected thereto, at any convenient place, either at the bilge as shown, or at one of the bilge keels, is a longitudinal rod B, secured to the ship in any convenient way as by the eye-bolts a. Hinged on this rod B are a series of metal plates C which are secured to the rod in any convenient way, as by the beads c. The outer surface of these plates should be made and kept as smooth as practicable, and in the wake of port holes or bull's-eyes of the ship the plates may be cut away and shutters provided to close the openings so made, but these details are omitted for the sake of clearness in the drawings. The upper ends of these plates C are connected to a similar rod D in any convenient way, as by the bead c'.

In order to stiffen the structure and interbrace the plates, I preferably provide a series of bars E hinged eccentrically, as at e, and having the short arm engaging a stop F on one adjacent plate and the long arm engaging a stop F' on the other adjacent plate. By having these bars E pivoted eccentrically, as shown, the longer ends may be swung upward and may be conveniently manipulated, and then allowed to swing down into the locking position shown in Fig. 4.

The series of plates may be raised or lowered by means of chains G, leading over guides H provided on the ship and connected to the winches I. These chains are connected at their lower ends to the rod D, connected to the upper ends of the plates C. While I have shown two such winches, it will be obvious that there may be any convenient number, depending on the length and weight of the system of plates.

To the upper portion of the plates I may provide floats J, of any suitable construction, such as cylindrical hollow metal bodies, which are secured to the rod D in any con-

venient way, as by means of the straps *j*. These floats tend to take the weight off the chains *G*, but may be omitted if desired.

In Fig. 5 I have shown an arrangement of 5 brace bars *M* connected to the plates and holding them rigidly spaced away from the side of the ship. These may be used supplemental to, or in place of the chain arrangement shown in Fig. 3.

10 The operation of the device is as follows:—In ordinary running the plates would be hauled up to the position shown in Fig. 3, or in full lines to the position shown in Fig. 2, then when nearing the danger zone the plates 15 may be lowered to the position shown in dotted lines in Fig. 2 and should be retained in this position until the danger zone has been passed. An automobile torpedo striking one of these plates would have its nose 20 deflected downward, and would pass beneath the bottom of the ship without striking the same. If the angle of the plates is sufficiently great, the firing pin of the torpedo will not strike the plate at all, being 25 screened by the rounded nose of the torpedo, and the torpedo will not explode; but even should it explode on striking one of these plates it will explode at such distance from the body of the ship that it would not do 30 the serious damage that would occur if the torpedo exploded directly against the side of the ship; it being well known that such explosions to be effective should be very close aboard, and that explosions in the 35 water at a short distance from the ship cause very little, if any, injury to the ship.

If desired, for convenience of manipulation the plates may be arranged in a series of minor groups, each operated independently. It will ordinarily be sufficient to 40 protect the main body of the ship, leaving the bow and stern exposed, and this main body of the ship is substantially straight fore and aft, so that the straight rods *B* 45 and *D* may be used with a straight line of plates connected thereto; but it will be obvious that curved rods and a curved series of additional plates may be applied to the bow and stern if desired, which may be lowered to the operative position, or raised to 50 the cruising position as may be desired.

It will be obvious that various other modifications might be made in the herein described apparatus, and in the construction, 55 combination and arrangement of parts which could be used without departing from the spirit of my invention.

Having thus described my invention what I claim and desire to secure by Letters Patent of the United States is:—

1. A protection for vessels against torpedoes, comprising a series of plates hinged to the bilge of the vessel below the water line, with chains for holding said plates 65 against the side of the ship in the cruising

position, and means for lowering said plates and holding them in the lowered position whereby the nose of an impinging automobile torpedo is deflected downward, substantially as described.

2. The combination with a vessel, of a longitudinal rod secured to the bilge of the vessel, and a series of plates hinged to said rod, with means for drawing said plates against the side of the ship and for easing the same down through a sufficient angle to deflect the nose of an automobile torpedo, substantially as described. 70 75

3. The combination with the body of a vessel, of a longitudinal rod secured thereto substantially at the bilge of the vessel, a series of plates hinged to said rod, a second rod secured to the top of said plates, and means attached to said second rod for swinging said plates to the raised or lowered position, substantially as described. 80 85

4. A protection for vessels against torpedoes, comprising a series of plates hinged to the body of the vessel below the water line, a series of floats secured above said plates, with means for holding said plates against the side of the ship in the cruising position, and for lowering said plates and holding them in the lowered position whereby the nose of an impinging automobile torpedo is deflected downward, substantially as described. 90 95

5. The combination with a vessel, of a longitudinal rod secured thereto below the water line, a series of plates hinged to said rod, a series of floats secured above said plates, and means for drawing said plates against the side of the ship and for easing the same down through a sufficient angle to deflect the nose of an automobile torpedo, substantially as described. 100 105

6. The combination with the body of a vessel, of a longitudinal rod secured thereto at or near the bottom of the vessel, a series of plates hinged to said rod, a second rod secured to the top of said plates, a series of floats secured to said second rod, and means attached to said second rod for swinging said plates to the raised or lowered position, substantially as described. 110 115

7. A protection for vessels against torpedoes, comprising a series of plates hinged to the body of the vessel below the water line, with means for holding said plates against the side of the ship in the cruising position, and for lowering said plates and holding them in the lowered position whereby the nose of an impinging automobile torpedo is deflected downward, with a brace bar hinged eccentrically to one of said plates, and having its arms engaging stops on the adjoining plates, substantially as described. 120 125

8. The combination with a vessel, of a longitudinal rod secured thereto below the water line, and a series of plates hinged to 130

said rod, with means for drawing said plates against the side of the ship and for easing the same down through a sufficient angle to deflect the nose of an automobile torpedo, 5 with a brace bar hinged eccentrically to one of said plates, and having its arms engaging stops on the adjoining plates, substantially as described.

9. The combination with the body of a 10 vessel, of a longitudinal rod secured thereto at or near the bottom of the vessel, a series of plates hinged to said rod, a second rod secured to the top of said plates, and means attached to said second rod for swinging 15 said plates to the raised or lowered position, with a brace bar hinged eccentrically to one of said plates, and having its arms engaging stops on the adjoining plates, substantially as described.

20 10. A protection for vessels against torpedoes, comprising a series of plates hinged to the body of the vessel below the water line, a series of floats secured above said plates, with means for holding said plates 25 against the side of the ship in the cruising position, and for lowering said plates and holding them in the lowered position whereby the nose of an impinging automobile torpedo is deflected downward, with a brace 30 bar hinged eccentrically to one of said

plates, and having its arms engaging stops on the adjoining plates, substantially as described.

11. The combination with a vessel, of a longitudinal rod secured thereto below the 35 water line, a series of plates hinged to said rod, a series of floats secured above said plates, and means for drawing said plates against the side of the ship and for easing the same down through a sufficient angle to 40 deflect the nose of an automobile torpedo, with a brace bar hinged eccentrically to one of said plates, and having its arms engaging stops on the adjoining plates, substantially as described. 45

12. The combination with the body of a vessel, of a longitudinal rod secured thereto at or near the bottom of the vessel, a series of plates hinged to said rod, a second rod secured to the top of said plates, a series of 50 floats secured to said second rod, and means attached to said second rod for swinging said plates to the raised or lowered position, with a brace bar hinged eccentrically to one of said plates, and having its arms engaging stops on the adjoining plates, substantially as described. 55

In testimony whereof, I affix my signature.

HORACE JAMES CHARLES.
